UNITED STATES PATENT OFFICE

164,368

INFORMAL CARD OR THE LIKE

Eugenie J. Jones, Webster Groves, Mo.

Application February 15, 1951, Serial No. 14,222

Term of patent 14 years

(Cl. D59—2)

To all whom it may concern:

Be it known that I, Eugenie J. Jones, a citizen of the United States, residing at Webster Groves, State of Missouri, have invented a new, original, and ornamental Design for an Informal Card or the like, of which the following is a specification, reference being had to the accompanying drawing, forming a part thereof.

The figure in the drawing shows a front view of an informal card illustrating my new design, the essential features of which reside in the portions shown in full lines, as well as in the lines of dots constituting the skirt of the dress on the figure.

I claim:

The ornamental design for an informal card or the like, substantially as shown and described.

EUGENIE J. JONES.
